INVENTOR

Albert Mueller,
By George Bowers, Attorney.

UNITED STATES PATENT OFFICE.

ALBERT MUELLER, OF NIEDER-SCHÖNWEIDE, NEAR BERLIN, GERMANY.

BUFFER-VALVE FOR HIGH-PRESSURE GASES AND FLUIDS.

SPECIFICATION forming part of Letters Patent No. 531,053, dated December 18, 1894.

Application filed September 21, 1893. Serial No. 486,132. (No model.) Patented in France July 6, 1893, No. 231,366, and in Belgium July 13, 1893, No. 105,542.

To all whom it may concern:

Be it known that I, ALBERT MUELLER, a subject of the King of Prussia, and a resident of the village of Nieder-Schönweide, near Berlin, Prussia, Germany, have invented certain new and useful Improvements in Buffer-Valves for High-Pressure Gases and Fluids, (for which I have obtained Letters Patent of France, No. 231,366, dated July 6, 1893, and of Belgium, No. 105,542, dated July 13, 1893,) of which the following is a specification.

My invention has reference to a buffer-valve, without spindle, designed for high-pressure gases and liquids, and particularly for liquid carbonic acid.

The object of the invention is to produce a valve that will answer present technical requirements, will be free from danger while being used or transported, can be handled in an easy and convenient manner, is small and light in weight, can be produced economically, and is durable in every respect.

The accompanying drawings represent my invention, and in the drawings—

Figure 1 shows a sectional view with the valve open; also showing interior and exterior attachments. Fig. 1^a is a detail of the side connection. Fig. 2 is a sectional view showing the valve closed with a protecting hood, and Fig. 2^a is a front view of the side connection closed.

In the drawings like parts are indicated by like letters of reference in the several views.

Referring to the drawings, A represents in full size the valve chest made of the best metal known. The interior of the same shows two smooth cylindrical passages of different diameters, also one with interior screw-thread. The lower cylindrical passage is occupied by a closely fitting piston a, to the lower end of which there is attached a hard rubber shank b driven into a suitable recess made for that purpose. The upper part c of the shank or piston is made of a conic form and between this conical part c and the lower cylindrical part a there is provided a receding curved neck, and around the same is placed a closely fitting buffer d extending to the walls of the valve chest and made of elastic rubber. Upon this buffer d there rests a closely fitting plate e surrounding the conical part c of the piston

and which by means of a sleeve h, provided with exterior and interior screw-threads, is forced down upon buffer d and causes the tightening of the piston in an upward direction. Plate e cannot be forced down any farther than is required for tightening the piston, as the movement of sleeve h is limited by an inner projection provided on valve chest A. The hand wheel g carries a short screw-threaded stem f engaging with the interior screw-thread on sleeve h. By turning hand wheel g to the extent of half a revolution to the right the piston is forced down sufficiently to bring hard rubber shank b in contact with the bottom of the valve chest which closes the mouth of passage q. This operation is performed without requiring any effort in turning the hand wheel.

For the purpose of opening the valve the hand wheel g is turned half a revolution to the left, whereby the upper end of the piston is freed and by the action of buffer d is automatically raised to the position which it must occupy when the valve is open. The discharge and the admission of the gases, when the valve is open, takes place through the small passages s and i which meet at right angles to each other. The connecting branch o is provided with exterior screw-thread for receiving the nut for coupling to it the connecting tube. Its interior screw-thread engages with a metallic stopper m which prevents the outflow of gas that may have gathered in the valve chest owing to leakage. If, while transporting the valve the same should become leaky, the gas which has escaped will, as soon as the stopper is slightly loosened, pass out through the small channel k (provided in the stopper) toward the operator, thus putting him on his guard. By this arrangement all danger attending the opening of the valve is done away with. The pin n on the stopper fits closely the passage i and prevents the closing of the continuation of the same by the packing disk l upon which the stopper presses as it is forced inward.

B represents the head of the flask. On top of the same there is shown a projecting ring r provided with outer screw-thread for attaching to it the projecting hood C, indicated in section in Fig. 2 and provided with a hex-

agonal upper projection to which the screw-wrench is applied. The interior of the hexagonal projection contains a cylindrical space within which is secured a hollow plug *t* by 5 means of a sleeve *u*, said plug inclosing in its lower recessed part a rubber plug *v* which as hood *C* is screwed downward comes to rest upon the central part of the hand wheel *g*, adapts itself to its surface and prevents a 10 loosening of the hand wheel while in transit. *D* indicates the screw-threaded attachment to the valve, (also represented full sized) by which the same is connected with the flask. At the lower end of attachment *D* there is 15 secured by screw-threads a strainer *p* which protects the passage *q*, located within said attachment and within the valve chest, against foreign bodies entering the same from the interior of the flask.

20 The valve is a structure complete in itself and after removal of the hood and of the stopper within the said outlet, is ready for use. The difficulties attending almost all other known valves, resulting from the necessity 25 of sending along attachments and tools, are thus obviated. It operates under a pressure of about three hundred atmospheres as promptly and readily as under a pressure of one atmosphere, and including the hood does 30 not weigh much more than one kilogram.

One of the principal difficulties attending the use of valves heretofore employed is that the spindle attached to the hand wheel, when 35 the valve is being opened is turned too much and the apparatus thereby becomes disarranged, which is a matter of much importance as the manipulation of the valve is generally left to inexperienced persons and in consequence, under high pressures, accidents are 40 very apt to occur. Another objection consists in the comparatively great dimension of the valves lengthwise as well as crosswise, in consequence whereof the protecting hood must also be made very high and of a large 45 diameter, and a blow inflicted upon the greatly projecting hood might lead to grave danger. Besides, the far greater weight of the old type of valve must be taken into consideration as the flasks are being constantly 50 shipped forward and backward.

Having thus described my invention, what I claim as new, and desire to secure by Letters Patent, is—

1. The combination with the valve chest A

provided with two compartments of different 55 diameters and a freely operating piston, as *a*, closely fitting the lowermost compartment and provided with a shank extending through the upper compartment and having a conical head and a receding curved neck below said 60 conical head, of an elastic buffer, as *d*, surrounding said neck, a stay plate, as *e*, resting on the elastic buffer and carried by the conical head of the aforesaid shank and means for forcing the stay plate down upon the buffer 65 and for exerting pressure on the piston shank, substantially as set forth.

2. In a valve for high-pressure gases and liquids, the combination with the valve chest provided with a branch outlet, as *o*, a safety 70 stopper for closing said outlet, said stopper having a longitudinal groove therein to permit the discharge of any gas which may escape between the valve and plug, during transportation, substantially as set forth. 75

3. The combination with a valve chest provided with a branch outlet, as *o*, of a safety stopper for closing said outlet and having a longitudinal groove therein, and a packing disk *l*, substantially as set forth. 80

4. The combination with a valve chest provided with a branch outlet, as *o*, in combination with the exit passage, of a safety stopper closing said outlet and having a longitudinal groove therein and a pin in its rear 85 end which is adapted to enter the aforesaid exit passage, and a packing disk as *l*, substantially as set forth.

5. The combination with the valve and a hand wheel for operating the same, of a flask 90 having a screw-threaded projection at the top, a hood inclosing the valve and adapted to be screwed onto the said projection of the flask and having a hollow central projection at its top, a hollow plug as *t* secured within 95 said projection and an elastic plug *v* fitting within said hollow plug *t* and which, as the hood is screwed onto the flask, turns around its axis and is forced against the hand wheel thereby preventing the accidental opening of 100 the valve during transportation, substantially as set forth.

In witness whereof I have hereunto set my hand in presence of two witnesses.

ALBERT MUELLER.
